SHIELD AND SEAT ARRANGEMENT

Frank L. Murphy and Carl H. Apel, Chicago, Ill., assignors to Pullman-Standard Car Manufacturing Company, Chicago, Ill., a corporation of Delaware

Application November 22, 1944, Serial No. 564,654

6 Claims. (Cl. 155—130)

1

The modern railroad day coach affords passengers many more comforts and conveniences than were ever provided in the old standard equipment. Today, each passenger enjoys, among many other conveniences, an individual seat independently adjustable to suit his own needs. Provisions are made to adapt these seats to both day and night use, so that each occupant may at any time recline or sit upright without reference to his neighbor occupying the next adjoining seat.

It is a common occurrence, however, in day coaches, and particularly in coaches where the modern adjustable seats are employed, for one occupant to fall asleep and slump over to a position where he crowds or otherwise interferes with the comforts of the occupant in the next adjoining seat. Often both occupants while sleeping in reclining positions face each other and cough or breathe into each other's face. These, of course, are undesirable conditions.

The present invention is intended to correct these conditions, and has as one of its principal objects the purpose of providing privacy as between the occupants of adjoining seats when such privacy is desired by either party. The device is flexible enough in its operation so that at all times when privacy is not desired there need be no obstruction whatever disposed between the seat occupants.

The foregoing constitute some of the objects and advantages of the invention, others of which will become apparent from the following description and the drawings, in which:

Fig. 1 is a more or less diagrammatic perspective view of a pair of adjoining seats shown in upright position with the separating shield entirely out of the way in its inoperative position;

Fig. 2 is a view corresponding to Fig. 1 but showing both seats in reclining position with the separating shield in its operative position;

Fig. 3 is an enlarged side elevational view of the separating shield and the center bracket mounting the shield on the seat base frame;

Fig. 4 is a front elevational view of the seats shown in Fig. 1;

Fig. 5 is a view corresponding to Fig. 3 but shows the relationship between the seat back and the separating shield when the back rests are in their upright positions;

Fig. 6 is a vertical sectional view taken on the line 6—6 of Fig. 5;

Fig. 7 is a horizontal sectional view taken on the line 7—7 of Fig. 5;

Fig. 8 is a top plan view of the spring clip that

2

holds the separating shield in the desired position;

Fig. 9 is a sectional view taken on the line 9—9 of Fig. 5;

Fig. 10 is a side elevational view corresponding to Fig. 5 but shows the relationship between the separating shield and the back rests at the time the back rests are in their reclining positions and the separating shield is in its operating position; and

Fig. 11 is a view corresponding to Fig. 10 but shows the separating shield in its inoperative position at the same time the back rests are in their reclining positions.

15 Though one embodiment only of the invention has been selected for the purpose of illustration, it is recognized that many modifications may be made without departing from the intended spirit and scope of the invention.

20 Referring now to Figs. 1 and 2, the invention is illustrated in conjunction with a pair of adjoining seats generally indicated at 25 and 26, comprising a pair of seat cushions 27 and 28 mounted on a seat base frame 29, and a pair of 25 adjustable back rests 30 and 31 movable between upright and reclining positions.

25 A separating shield 32 forming the subject matter of the invention is illustrated in Fig. 1 as being in its inoperative position, and is at that time disposed in a recess 33 formed between the adjacent seat back rests 30 and 31. This shield comprises a panel substantially corresponding in width and height to the corresponding dimensions of the back rests 30 or 31. The

30 forward edge of the shield has a contour corresponding substantially to that of one of the seat backs. In Fig. 2, the back rests 30 and 31 are illustrated in their reclining positions as distinguished from their upright positions shown in

35 Fig. 1 and the separating shield 32 is shown in its operative position in Fig. 2 extending outwardly from the front faces of the back rests 30 and 31 to provide an obstruction between the two seats.

40 Referring to Figs. 3 and 9, a center bracket 34 is mounted on the seat base frame 29 and is fastened to the base frame by rivets or the like (not shown) extending through a horizontal leg 35 forming the lower part of the center bracket 34.

45 The separating shield 32 may be made of wood—such, for example, as plywood—and is fastened at its lower edge on both sides by metal plates 36 (see Fig. 7). The separating shield 32 is fastened to the center bracket 34 by means 50 of a bracket, generally indicated at 37, which, as

best shown in Fig. 7, comprises a pair of fastening members 38 and 39, which together form bifurcated arms between which the plates 36 and the separating shield 32 is held. The center bracket 34 is provided with a boss 40 grooved as at 41 (see Fig. 7) to provide half of a journal, the remaining half being provided by a separate journal member 42 bolted to the boss 40 as shown at 43.

This center bracket 34 forms the support for the back rests 30 and 31 and for the separating shield 32. A shaft segment 44 (see Fig. 9) is provided for each back rest 30 and 31, about which the back rests pivot when moving between upright and reclining positions. These shaft segments 44 terminate in the journals 41.

Each arm 38 and 39 of the bracket 37 is provided with a hole 45 through which the shaft segments 44 pass, as best shown in Figs. 7 and 9. Thus, the separating shield 32 between each seat is mounted on the shaft segments 44.

As shown, for example, in Figs. 5 and 9, one of the plates 36 and the separating shield 32 at its lower end is provided with an arcuate slot 46 into which slot projects a lug 47 fastened to one seat back rest—for example, seat 30, as shown in Fig. 9. This lug 47 moves with back rest 30, and when the back rest is in its upright position shown in Fig. 5 the lug 47 is disposed in the upper end of slot 46. As the lug 47 moves with seat back 30, it rotates about the shaft segment 44 as its center and moves in the slot 46 in a downward direction until it reaches the lower extremity of the slot. The position of the back rest corresponding to this lower position of the lug 47 is somewhere between its upright position and its full reclining position, and therefore as the back rest is rotated further toward its full reclining position the lug 47 engages the lower end of the slot 46, and then applies a torque to the separating shield 32, moving the shield about its center until the back rest 30 is in its full reclining position, shown, for example, in Fig. 10. All of this movement of the separating shield 32 is accomplished by the movement of only one back rest; namely, the one designated by the numeral 30. The second back rest 31 can either be in upright position or in full reclining position, as it has no effect whatever on the separating shield 32. When both back rests are disposed in their upright positions, the separating shield 32 assumes the position substantially flush or slightly behind the back rest so as to be out of the way. It is only when the back rests are reclined that the separating shield serves as a dividing wall.

As shown in Figs. 5, 10, and 11, a spring clip 48 mounted on the center bracket 34 by means of a rivet, for example, as shown at 49, is provided with a curved contacting portion 50 adapted to engage any of a plurality of indentations 51 disposed in the separating shield 32. This spring clip 48 has sufficient strength to hold the separating shield 32 in one of its selected positions. As illustrated in the drawings, there are three such indentations 51 indicated at 51a, 51b, and 51c, and consequently the separating shield 32 may assume one of three selected positions; namely, a full upright position, an intermediate position, and a full reclining position, the latter of which allows for the movement of the separating shield to an inoperative position even when the seat back rest 30 is in its full reclining position. In other words, the seat occupants may wish to converse even when the seat back rests 30 and 31

are in their full reclining positions. This is accomplished by moving the separating shield 32 by hand to its full reclining position illustrated in Fig. 11. The other two positions of the shield 32 are assumed automatically in response to the positioning of the seat back 30.

As illustrated, the lug 47 operating the separating shield 32 is mounted on seat back rest 30, which back rest is disposed nearest to the central aisle of the car, generally indicated at 52 in Fig. 4. The advantage of this arrangement is that a car attendant, such, for example, as a porter, can adjust the seat back rest 30 to operate the separating shield 32 if requested to do so by the occupant of seat 25. There is no need at any time for the occupant of seat 26 to be concerned with the separating shield 32 unless he wishes to move it to its full reclining position at the time both back rests are reclined. At all other times, the operation of the separating shield 32, in so far as concerns the occupant of seat 26, is fully automatic with the operation of back rest 30.

The present invention is intended to be simple both in construction and operation. Many modifications are apparent to the present inventors, and it is recognized that they will also be apparent to those gaining knowledge of the present disclosure. All requirements of the occupants of both seats, however, are satisfied with the arrangement disclosed herein.

We claim:

1. A pair of seats arranged side by side including a seat frame, a seat cushion and an adjustable back rest for each seat, an adjustable separating shield between the back rests, an upstanding bracket on the seat frame between the seat cushions, means pivotally mounting the shield adjacent to its lower end to the bracket, the shield having a lower, horizontal notched edge, spring means on the bracket adapted to engage a selected notch to hold the shield in adjusted position, the shield projecting forwardly of the back rests in one position of its adjusted positions, said shield when projected beyond the back rest preventing lateral access from one back rest to the other.

2. A seat comprising a pair of back rests disposed side by side, support means mounting each back rest independently for movement between upright and reclining positions, a shield disposed between the back rests, support means mounting the shield adjacent to its lower end for pivotal movement between selected positions corresponding to upright and reclining positions of the back rests, locking means adapted to engage the shield to hold the latter in its selected positions, and means on one back rest adapted to engage the shield to move the shield to upright position when the last mentioned back rest is moved to upright position.

3. A seat for double occupancy comprising a pair of pivotally mounted back rests disposed side by side adapted to move from upright to intermediate and reclining positions, the back rests when both are disposed in upright, intermediate or reclining positions having their front faces substantially flush; a separating shield disposed between the back rests and being substantially coextensive with the height of the back rests, support means on the seat mounting the shield for pivotal movement adjacent to its lower end so that the shield may move from upright to intermediate and reclining positions corresponding to said positions of the back rest, locking

means adapted to engage the shield to hold the latter in selected position, and means on one back rest engaging the shield for moving the shield from its reclining position to its upright position, both back rests being movable to their intermediate positions independently of the shield.

4. A seat for double occupancy comprising a pair of pivotally mounted back rests disposed side by side adapted to move from upright to intermediate and reclining positions, the back rests when both are disposed in upright, intermediate or reclining positions having their front faces substantially flush, a separating shield disposed between the back rests and being substantially coextensive with the height of the back rests, support means on the seat mounting the shield for pivotal movement adjacent to its lower end so that the back rest may move from upright to intermediate and reclining positions corresponding to said positions of the back rest, locking means adapted to engage the shield to hold the latter in either position, and means operatively connecting one back rest with the shield for moving the shield from its reclining position to its upright position, both back rests being movable to intermediate position independently of the shield.

5. A seat for double occupancy comprising a pair of pivotally mounted back rests disposed side by side adapted to move from upright to a second position, the back rests when both are disposed in upright or their second positions having their front faces substantially flush, a separating shield disposed between the back rests and comprising a wall-like member extending downwardly from a position adjacent to the top of the back rests, support means on the seat mounting the shield for pivotal movement there-

of from upright to a second position corresponding to said positions of the back rests with the axis of said movement corresponding to the axis of the movement of the back rests, locking means adapted to engage the shield to hold the latter in either position, and means operatively connecting one back rest with the shield for moving the shield from its second position to its upright position, both back rests being movable to their second position independently of the shield.

6. A seat comprising a pair of back rests disposed side by side, means mounting each back rest independently for movement between upright and a second position, a shield disposed between the back rests and comprising a wall-like member extending downwardly from a position adjacent to the top of the back rests and adapted to assume a position corresponding with upright position of the back rests, support means mounting the shield for pivoting independently of the back rests, the back rests being adapted to pivot independently between the upright and the second position while the shield remains in upright position.
